UNITED STATES PATENT OFFICE.

CHARLES LAYTON, OF MOUNT PLEASANT, PENNSYLVANIA.

DUMPING MINE-CAR.

1,124,147.

Specification of Letters Patent.

Patented Jan. 5, 1915.

Application filed February 24, 1914. Serial No. 820,747.

To all whom it may concern:

Be it known that I, CHARLES LAYTON, a citizen of the United States, residing at Mount Pleasant, in the county of Westmoreland and State of Pennsylvania, have invented certain new and useful Improvements in Dumping Mine-Cars, of which the following is a specification.

My invention appertains to means for facilitating the automatic dumping of mining cars.

In carrying out this invention I contemplate the provision on the body of a mine or similar car of mechanism adapted to be actuated by an obstacle in the path of movement of the car to release certain locking means by which the dumping door of the car is normally maintained in a closed position.

While the invention is particularly adapted for use in connection with mining cars, it will be evident on reference to the following description that other types of cars, or dumping vehicles even, wherein a dumping door is employed may have the invention applied thereto with resultant advantage.

With the above and other objects in view, this invention consists in the construction, combination and arrangement of parts all as hereinafter more fully described, claimed and illustrated in the accompanying drawings, wherein:

Figure 1 is a side elevation of a mining car showing the preferred embodiment of the invention. Fig. 2 is a bottom plan view. Fig. 3 is a section taken about on the line 3—3 of Fig. 1, looking forwardly. Fig. 4 is a diagrammatic view showing more clearly the manner in which the car is dumped by engagement of an obstacle with the shoe, said obstacle being preferably the horn of a dumping rail.

Throughout the following detail description, and on the several figures of the drawings similar parts are referred to by like reference characters.

The car A illustrated in the drawings may be of any conventional type having at least one end thereof the end gate or dumping door B. The door B swings at its upper end upon a cross bar 1 and any suitable means may be provided intermediate the parts B and 1 permitting outward swinging of the door at the lower portion in the action of dumping the contents of the car

body. The car A has the usual trucks and supporting wheels C. The door B is normally held in its closed position by means of a locking bolt 2, said bolt being slidable vertically and loosely through an opening in the bottom of the car A. At its lower end the bolt 2 is pivotally connected as at 3 with the laterally and inwardly extending arm 4 of a rock shaft 5 arranged beneath the bottom of the car adjacent to the front end of the latter. The shaft 5 is supported in suitable bearings 6 bolted or otherwise fastened to the car bottom. A coil spring 7 encircles the rock shaft being attached thereto at one end and being anchored at the other end to the car. The normal tendency of the spring 7 is to force the arm 4 upward against the bottom of the car and hold the bolt 2 projecting into operative engagement with the outer side of the door B. At its rear end the shaft 5 carries a vertical arm 8 detachably secured at its lower end to the shaft so that the arm may be removed for the purpose of arranging the spring 7 on, or detaching said spring from the shaft 5. On one side of the car A is mounted a shoe 9 secured at its front end to the car and bearing intermediate its ends against the arm 8 at the outer side of the latter.

The arm 8 is normally held in a position inclining vertically and outwardly from the car, owing to the action of the spring 7 on the shaft 5, and thus the rear end of the shoe 9 by its engagement with the arm 8 is likewise held in a position inclining outwardly and rearwardly from the car. A guide member 10 projects laterally and inwardly from the shoe 9 and extends through a keeper 11 attached to the bottom of the car. The purpose of the guide member 10 is to hold the shoe 9 in proper position in relation to the arm 8 preventing sagging tendencies of the shoe which is movably connected, of course, at its front end with the car.

Describing now the operation of the invention, it will be apparent that as the car A moves forwardly the mechanism for controlling the dumping of the door B is so arranged as to permit an obstacle in the path of the shoe 9 to strike said shoe and force the same inwardly. When the shoe is thus operated its inward movement will be imparted to the arm 8 thereby rocking the shaft 5 and forcing the arm 4 downward. This movement of the arm 4 withdraws the

bolt 1 from its engagement with the door B and said door is then free to swing open and discharge the contents of the car in an obvious manner.

- 5 The guide member 10 of the shoe 9 may be formed integral with said shoe or it may be a separate member as desired. Where the shoe 9 is made, however, of a piece of heavy metal, the member 10 will preferably 10 be an inwardly bent extension of said metal twisted into a plane at a right angle to that of the shoe so as to slide freely through the keeper 11. The obstacle by which the shoe 9 is operable is not illustrated but may comprise a standard arm or other projecting part located at a side of the track over which the car A travels and capable of striking the shoe during the progress of the car.
- 15 It is contemplated that the dumping car to which the invention is applied shall be of the type adapted to tilt on the dumping rails ordinarily provided at mine dumps, one of the horns or curved ends of the rails 20 being adapted to engage the shoe 9 and force the same inward to release the bolt 2, just as the car is tilted. In Fig. 4 a dia- 25 grammatic view of the dumping of the car

is given indicating the manner in which the horn D of a dumping rail is adapted to engage and operate the shoe 9.

Having thus described my invention, what I claim as new is:

In combination, a mine car, a dumping door at one end of said car, a rock shaft mounted on the bottom of the car and having an arm projecting therefrom at one end, a locking bolt engaging the door to hold the same closed and pivotally connected with said arm, a vertically extending arm projecting from the rock shaft, a spring encircling the rock shaft and holding the last mentioned arm in spaced relation to the car and maintaining the locking bolt in engagement with the door, a shoe movably secured to a side of the car and engaged by the last-mentioned arm, a guide member projecting from the shoe, and guiding means on the car coöperating with said guide member.

In testimony whereof I affix my signature in presence of two witnesses.

CHARLES LAYTON.
